UNITED STATES PATENT OFFICE

107,984

DESIGN FOR A PORTABLE FOOD MIXER

William F. Allenby and Carlton H. Willman,
Bridgeport, Conn., assignors to General Electric Company, a corporation of New York

Application September 28, 1937, Serial No. 71,846

Term of patent 14 years

To all whom it may concern:

Be it known that we, William F. Allenby and Carlton H. Willman, citizens of the United States, residing at Bridgeport, in the county of Fairfield, State of Connecticut, have invented a new, original, and ornamental Design for a Portable Food Mixer, of which the following is a specification, reference being had to the accompanying drawings, forming part thereof.

The accompanying drawings show in Fig. 1 a perspective view of a portable food mixer embodying our new design, and in Figs. 2, 3 and 4 a front elevational view, a side elevational view and a top plan view respectively of the food mixer of Fig. 1, the side elevational view in Fig. 3 showing an element of the food mixer in a different operative position than in Figs. 1, 2 and 4.

We claim:

The ornamental design for a portable food mixer, substantially as shown and described.

WILLIAM F. ALLENBY.
CARLTON H. WILLMAN.
